AUTOMATIC HEADLIGHT DIMMER

Harold A. Goldsmith, Elmhurst, Herbert Herz, Forest Hills, and Arthur Z. Guterman, New Rochelle, N. Y., assignors to Magnetic Amplifiers, Inc., a corporation of New York

Application August 24, 1954, Serial No. 451,766

3 Claims. (Cl. 307—41)

This invention relates to a device for automatically dimming headlights of an automobile upon the approach of another automobile.

Among the objects of the invention is to provide a device which acts automatically to dim the headlights of an automobile or shift from a high to a low beam when another automobile approaches within a certain distance.

All automobiles are provided with manually operated dimming devices but often the driver forgets to dim the light when another car approaches and often the driver does not know whether he is using the dim or the undim lights for driving.

There are a number of electronic and electric circuits available which are sensitive to light of a certain intensity which may be employed as an automatic dimmer but for the most part, at least, such known circuits are bulky, unreliable, and/or expensive. In this specification the expression to "dim the lights" will be understood to cover either a dimming or a shifting from high beam to low beam.

Among other objects of this invention is to provide a simple, inexpensive, rugged and reliable device for automatically dimming the headlights of an automobile.

These and other objects ancillary thereto are obtained by combining a photosensitive device in a circuit with a low voltage magnetic amplifier and a relay which controls the light dimmer switch. The circuit is energized from a vibrator device which in turn may be driven from the automobile battery. The photosensitive device is desirably shielded on all the sides except the side directed toward the approaching automobiles. When little or no light strikes the photosensitive device, this device acts as a good rectifier and presaturates the magnetic core of the magnetic amplifier. When the magnetic core is presaturated, it forms a very low impedance path and the power is transferred almost entirely to the relay which is therefore in the energized state. When light of sufficient intensity strikes the photosensitive device, it becomes a poor rectifier and passes more alternating current. When this happens, the coil and the magnetic amplifier is deenergized and becomes a high impedance path absorbing most of the power. The relay therefore is deenergized whereupon the light switch is shifted to dimming position.

One phase of this invention is based on the discovery that no separate rectifier is required in such a circuit.

Another phase of the invention is based on the discovery that a magnetic amplifier consists of only one coil, one core and only two leads.

Obviously, if desired, rectifiers could be added or a more complex magnetic amplifier could be employed.

Various types of photosensitive devices may be employed such as a germanium photo-diode, a selenium cell, a photo-transistor, etc.

In the drawing, the figure shows a diagrammatic circuit for the device of the invention.

The automobile battery 10 which may be of 6 or 24

2

volt type connected to a vibrator device at 11, 12, and the alternating current produced in the vibrator is obtained from terminals 13 and 14. The vibrator is of conventional type such as employed in automobile radios. The terminal 13 is connected to one side of the photosensitive device 15. The other side of the photosensitive device 15 is connected to one terminal of the two terminal magnetic amplifier 16. The other terminal of the magnetic amplifier 16 is connected to relay 17. The order of connecting the magnetic amplifier 16, photosensitive device 15 and relay 17 can be changed.

The relay 17 closes the circuit between line 21 and either line 22 or line 23. In the device shown terminal 18 and line 23 operate the bright light filament of the automobile headlight bulbs and terminal 19 and line 22 operate the dimming filaments of the headlight bulbs.

In operation, substantially the entire circuit including the magnetic amplifier, the relay, the vibrator and the photosensitive device may be mounted in a small housing at the driver's side of or on the inside of the car with the photosensitive device exposed to receive light from the headlights of the approaching cars. When the lights are turned on the circuit operates to maintain the bright lights on. When an automobile from the opposite direction approaches within a certain distance the lights of the approaching car shining on the photosensitive device 15, make it a poor rectifier and a better conductor of alternating current whereupon relay 17 is deenergized and the dim lights switched on. When the approaching car passes, the relay is again energized and the bright lights again switched on.

It will be seen that the circuit avoids all use of photomultiplier tubes or other vacuum tubes. Photomultiplier tubes require high voltages that may be dangerous to handle whereas the device of this invention is entirely safe. The magnetic amplifier provides a very rugged and reliable means for controlling the circuit. The device of the inventor requires practically no maintenance. Since no vacuum tubes are employed the device will not be influenced by shock normally encountered in driving over rough roads. The vibrator device requires a very low power drain on the battery, and the entire device is capable of being packaged in one small unit which requires no installation of accessories under the hood.

The features and principles underlying the invention described above in connection with specific exemplifications will suggest to those skilled in the art many other modifications thereof. It is accordingly desired that the appended claims shall not be limited to any specific feature or details thereof.

I claim:

1. In a device for the automatic dimming of bright and dim type headlights of a first vehicle upon the approach of another headlighted vehicle, a first electrical circuit for energizing the dim headlights of said vehicle, a second electrical circuit for energizing the bright headlights of said first vehicle, relay operable switch means having at least two positions, a first position adapted to complete said first circuit and a second position adapted to complete said second circuit, a third circuit comprising a source of alternating current, a photosensitive device, a magnetic amplifier and an electrical relay connected in series, said relay including an activating circuit which is connected in series with said third circuit, said relay being operatively connected to said relay operable switch means, said photosensitive device being of the electrode type and adapted to operate as a conductor when light of a certain minimum intensity is impinged thereon and adapted to operate as a rectifier at other times, whereby said photosensitive device normally acts

as rectifier to saturate the magnetic amplifier and energize the relay to complete said second bright light circuit, said photosensitive device being transposed to a conductor when light of a certain minimum intensity from the headlights of an approaching vehicle impinges thereon whereupon the relay is deenergized to complete said first circuit of the dim lights.

2. The device as set forth in claim 1 in which the magnetic amplifier has only one coil, one core and two terminals.

3. The device as set forth in claim 1 in which the means for supplying alternating current is a vibrator device.
